RECIPROCATING PUMP

Kenneth A. Ellis, Evansville, Wis., assignor to Baker Manufacturing Company, Evansville, Wis., a corporation of Wisconsin

Application September 25, 1952, Serial No. 311,390

2 Claims. (Cl. 103—175)

This invention relates to a reciprocating pump of the type in which the fluid is drawn into a suction chamber through the inlet pipe and then into the cylinder of the piston on one stroke of the latter and, on the return stroke, is forced into a discharge chamber and out through an outlet pipe.

The general object is to provide a pump of the above character with a new and improved casing which permits quick and easy access to the pump parts without disconnecting the inlet and outlet pipes.

Another object is to form the casing in a plurality of readily separable sections with the suction and discharge chambers formed in one section to which the inlet and outlet pipes are connected so that this section and the pipe connections need not be disturbed in making normal repairs on the pump.

A more detailed object is to form the casing in three sections, one defining the suction and discharge chambers, one housing the piston and one enclosing the reciprocating mechanism, to permit the pump to be dismantled easily.

Still another object is to mount the motor for driving the pump in a novel manner on the stationary casing section so that neither the motor nor the electrical connections therefor need be disturbed preparatory to repairing the pump.

A further object is to mount the intake and discharge valves of the pump in a novel and advantageous location between two of the detachable casing parts.

The invention also resides in the novel arrangement of the parts to provide a two pedestal support for the pump.

Other objects and advantages of the invention will become apparent from the following detailed description taken in connection with the accompanying drawings, in which:

Figure 1 is a perspective view of a pump with a casing embodying the novel features of the present invention.

Fig. 2 is an exploded view of the casing.

Fig. 3 is a fragmentary sectional view taken along the line 3—3 in Fig. 2.

Figs. 4 and 5 are fragmentary sectional views taken along the line 4—4 and 5—5 in Fig. 3.

For the purpose of illustration, the invention is shown in the drawings embodied in a reciprocating pump driven by an electric motor 11 mounted on a pump casing 12 and connected by a belt 13 to a flywheel 14 which reciprocates a piston 10 through the medium of a reciprocating mechanism 15 disposed within the casing. This mechanism comprises a crank 16 fast on the shaft 17 of the flywheel and a pitman or connecting rod 18 pivoted at one end to the crank and at the other end to a cross-head 19 which, in turn, is connected to the outer end of the piston rod 20.

In the present instance, the pump is double-acting and, for this purpose, the piston 10 slides in a cylinder 21 which opens at opposite ends into separate closed cham-

bers 22 and 23 (Fig. 3). The piston chamber 22 communicates with a suction chamber 24 (Fig. 4) through a port 25 and with a discharge chamber 26 through a port 27 while the piston chamber 23 similarly is connected to the suction and discharge chambers through ports 28 and 29 respectively (Fig. 5). The ports 27 and 29 are closed in a conventional manner by check valves 30 seated on the discharge side of the ports and the ports 25 and 28 are closed by check valves 31 on the piston side. Thus, when the piston 10 moves to the right as viewed in Fig. 3, fluid such as water entering the suction chamber 24 through an inlet pipe 32 is drawn into the chamber 23 through the port 28. At the same time, water in the chamber 22 is forced through the port 27 and into the discharge chamber 26 from which it may be delivered to a tank 33 through an outlet pipe 34. In a similar manner, water is drawn into the chamber 22 and forced out of the chamber 23 on the return stroke of the piston.

In accordance with the present invention, the casing 12 is constructed in a novel manner to permit the suction and discharge chambers 24 and 26 to be formed in a separate section 35 to which the inlet and outlet pipes 32 and 34 are connected so that this section may be stationary and need not be moved when it is desired to gain access to the pump parts normally requiring repair such, for example, as the valves 30 and 31, the piston 10, the crank and piston rod joints. In this way, the connections of the pipes may be comparatively permanent and normally it is unnecessary to disconnect the pipes in order to repair the pump. Preferably, the remaining portion of the casing is divided into two sections 36 and 37, readily separable from each other and from the first section, the second section housing the piston 10 while the third encloses the reciprocating mechanism 15.

Herein the casing section 35 is an elongated upright hollow casting of generally rectangular cross section and is divided by a horizontal partition 38 (Figs. 4 and 5) into upper and lower chambers which form the discharge and suction chambers 26 and 24 respectively. As shown in Figs. 3 and 5, the inlet pipe 32 is threaded into a side wall 39 of the casing adjacent the lower end thereof and the outlet pipe 34 is threaded into the rear wall 40 of the casing adjacent the upper end so that each communicates with its respective chamber. On its front wall 41, the casing section 35 is machined to form a flat generally square vertical surface 42 extending above and below the partition 38. Four spaced ports 43 (Fig. 2) two communicating with each of the chambers 24 and 26 extend through and are disposed in the four quadrants of the surface 42 so as to be aligned with the four valve-controlled ports 25, 27, 28, and 29.

Depending from the partition 38 and extending across the casing section 35 between the front and rear walls 40 and 41 is a wall 44 (Fig. 4) by which any air coming into the suction chamber 24 is confined in the rear of the casing section 35 so that it cannot be drawn into the piston chambers 22 and 23. In one corner of the casing section 35 is a vertical passage 45 (Fig. 3) extending from the top of the casing down through the partition 38 and closed at its upper end by a threaded cap 46 so that the suction chamber may be filled with water to prime the pump.

To prevent the pressure in the discharge chamber 26 from becoming too great, a relief valve 47 closes a port 48 in the wall 49 between the passage 45 and the discharge chamber. Herein the relief valve comprises a disk 50 coacting with a seat 51 pressed into the wall 49. A tubular projection 52 on the back of the valve disk slides on a pin 53 rigid with a screw 54 threaded into the rear wall 40 of the casing section 35 and a

calibrated compression spring 55 acting between the screw 54 and the disk 50 urges the latter against the seat 51. Thus, under normal operating conditions, the port 48 is closed by the valve 47 but, when the pressure in the discharge chamber exceeds a desired value, the valve opens against the spring 55 and permits the water in the discharge chamber to be returned to the suction chamber 24.

The second section 36 is cast to form a housing for the piston 10 and is divided into the piston chambers 22 and 23 by an internal vertical wall 56 (Fig. 3) having a tubular central portion 57. A brass sleeve is pressed through the portion 57 to form the cylinder 21 of the pump. A vertical side wall 58 of the casting parallel to the cylinder 21 is machined to provide a flat external surface 59 opposing the surface 42 on the casting 35. Four ports 60, two communicating with each of the piston chambers, extend through the surface 59 and are spaced apart to be aligned with the valved ports 25, 27, 28 and 29 and the ports 43 through the surface 42 on the casing section 35.

In the present instance, the valved ports 25, 27, 28 and 29 are formed in the four quadrants of a separate plate 61 which is disposed between the opposing surfaces 42 and 59 on the casing sections 35 and 36 and supports the valves 30. Proper alignment of the ports in the plate with the ports in the casing sections is insured by dowel pins 62 (Fig. 2) projecting laterally from the surface 42 and through holes in the plate. When the latter is in place against the surface 42, the two casing sections 35 and 36 are fastened together by two bolts 63 projecting through the casing section 35 and holes in the valve plate 61 and threaded into the casing section 36. By tightening the bolts, the two sections are drawn together clamping the plate between the surfaces 42 and 59. Suitable gaskets 64 on opposite sides of the plate may be provided to obtain a watertight connection.

To house the reciprocating mechanism 15, the third hollow casing section 37 is an elongated horizontal casting aligned with the casing section 36. The opposing ends of the sections 36 and 37 are machined to form flat mating surfaces 65 and 66 which abut against each other and the two sections are clamped together by two bolts 67 projecting lengthwise through the section 36 and threaded into the section 37. As shown in Fig. 3, the piston rod 20 is disposed within the section 37 and projects through a hole 68 in the surface 65 and into the cylinder 21 in the section 36. To seal the piston chamber 23, a cylindrical seal 69 is pressed into the hole 68 and closes the latter around the piston rod. The back of the casing section 37 is closed by a casting 70 (Fig. 2) bolted in place and having a lateral extension 71 in which the crankshaft 17 is journaled. A rectangular opening 72 (Fig. 2) in the front of the casing section 37 permits access to the reciprocating mechanism 15 and is closed by a removable cover plate 73.

Depending from the outer end of the casing section 37 and cast integrally therewith is a leg 74 from the lower end of which projects a slotted lug 75. Similar slotted lugs 76 project outwardly from the lower end of the front and rear walls 41 and 40 of the casing section 35 so that the pump may be secured to a suitable stationary frame or support (not shown) by bolts 77 (Fig. 1) projecting through the slots in the lugs. Thus the leg 74 and the casing section 35 form a two pedestal support for the pump.

Preferably, advantage is taken of the stationary mounting of the casing section 35 to support the motor 11 so that the electrical connections to the latter need not be disturbed as an incident to dismantling the pump preparatory to making normal repairs. To this end, a plate 78 is pivoted on a lug 79 on the side of the section 35 adjacent the upper end thereof and one side of the motor frame is fastened to the plate by a bolt 80. A screw 81 threaded through the free end of the plate 78

5 abuts against a projection 82 on the upper side of the casting 37 to hold the motor stationary when the pump is assembled. By turning the screw 81, the motor may be tilted about the axis of the pivot 79 to tighten or loosen the belt 13.

In operation, water is poured into the suction chamber 24 through the vertical passage 45 to prime the pump and the cap 46 is replaced. The motor 11 then is started to turn the crank 16 and reciprocate the piston 10. On the forward stroke of the piston, water is drawn from the suction chamber through the port 28 and into the piston chamber 23. On the return stroke, the water drawn into the chamber 23 is forced into the discharge chamber 26 and out through the outlet pipe 34 and, 15 at the same time, water from the suction chamber is drawn into the forward piston chamber 22. As the cycle is repeated, water is alternately drawn into and forced out of the two piston chambers 22 and 23.

It will be observed that the pump with the casing 12 as 20 described above is comparatively simple to manufacture and provides easy access to the parts, such as the valves 30 and the piston 10, which normally are the parts requiring repair and replacement. For example, the valve plate 61 may be removed simply by loosening the bolts 25 63 and swinging the casing section 36 slightly away from the section 35. By loosening both the bolts 63 and the bolts 67, the three casing sections 35, 36, and 37 may be separated so that the seal 69 and the piston 10 also are accessible. Since the parts generally requiring repair are 30 in the sections 36 and 37, the section 35 need not be moved and thus, as a rule, it is not necessary to disturb either the electrical connections to the motor 11 or the connections of the inlet and outlet pipes 32 and 34. In addition, the arrangement permits the discharge chamber 35 26 to be above the suction chamber 24 so that any air in the system flows up and out through the outlet pipe 34 rather than being trapped in one of the piston chambers 22 and 23. Further, by resting the pump on the casing section 35, a two pedestal support is provided simply by 40 adding the leg 74.

I claim as my invention:

1. In a pump adapted to be mounted on a base and having a piston, a rod projecting from the piston, a rotary crank, and a pitman connecting said crank and rod, the combination of, a first rigid hollow casing section 45 adapted to be stationarily secured to said base and defining separated suction and discharge chambers each opening outwardly through the casing section for communication with inlet and outlet pipes respectively, a member 50 mounted on said casing section and providing a support for a motor driving said crank, a flat machined surface facing outwardly from a vertical side wall of said casing section and having laterally spaced ports therethrough respectively communicating with said suction and discharge 55 chambers, a second hollow casing section defining a horizontal cylinder for said piston and having a first flat vertically disposed machined surface with valve-controlled ports extending therethrough and communicating with opposite ends of the cylinder, fastening elements detachably joining said casing sections with said machined surfaces 60 opposing each other, said second casing section having a second flat machined surface disposed in a vertical plane and at right angles to said first surface, a rigid hollow part 65 supporting said crank and having a flat machined surface abutting against and mating with the second machined surface on said second section, said piston rod extending horizontally outwardly through the second surface of said second section and into said part to connect with said crank, and means detachably connecting said part and said second section, whereby to permit access to the moving parts of the pump and to said valve-controlled ports without removing said first section from the base and without disconnecting said pipes and said motor.

2. A pump as defined in claim 1, in which the hollow

part includes means for supporting said part on said base
and independently of said first casing section.
